UNITED STATES PATENT OFFICE.

JOSEPH F. BERG, JR., OF PLAINFIELD, NEW JERSEY.

DESIGN FOR A NECKTIE-HOLDER.

SPECIFICATION forming part of Design No. 26,613, dated February 9, 1897.

Application filed October 28, 1896. Serial No. 610,368. Term of patent 14 years.

To all whom it may concern:

Be it known that I, JOSEPH F. BERG, Jr., a citizen of the United States, residing at Plainfield, in the county of Union and State of New Jersey, have invented and produced a certain new and original Design for a Necktie-Holder; and I do declare the following to be a full, clear, and exact description of the invention, such as will enable others skilled in the art to which it appertains to make and use the same.

The invention has relation to a new and useful design for a necktie-holder; and it consists of a necktie-holder of the configuration and ornamentation shown in the accompanying drawings, in which—

Figure 1 is a perspective view of the necktie-holder; and Fig. 2 is a top edge view, and Fig. 3 an end view, of the same.

The leading feature of my design is a necktie-holder having a flattened dovetail central loop 1, from the upper ends of the sides of which project laterally two arms, which are curved in the arc of a circle and are formed with eyes 2, from which project downward in a different plane arms 3, the lower ends of which are bent upward, as at 4.

What I claim is—

The design for a necktie-holder, as herein shown and described.

In testimony whereof I hereunto affix my signature in presence of two witnesses.

JOSEPH F. BERG, JR.
